UNITED STATES PATENT OFFICE.

CHARLES E. MENDENHALL, OF DAYTON, OHIO.

MAIL-BOX.

No. 900,756.

Specification of Letters Patent.

Patented Oct. 13, 1908.

Application filed October 19, 1907. Serial No. 398,154.

To all whom it may concern:

Be it known that I, CHARLES E. MENDENHALL, citizen of the United States, residing at Dayton, in the county of Montgomery and 5 State of Ohio, have invented certain new and useful Improvements in Mail-Boxes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in letter boxes and possesses the new and useful features hereinafter described and claimed.

The object of the invention is to provide 20 means for indicating the times of collections of mail and which makes it necessary for the carrier or mail collector to remove the mail from each box in order to indicate to the public the time of the next succeeding collection, or make it incumbent upon him 25 to render a suitable explanation to the superintendent of mails for his failure to collect the mail at the proper time or times, and further, by means of the device the superintendent or inspector is enabled to keep track 30 of the mail collectors in the discharge of their duties.

The means comprise an indicating dial with certain specific mechanism interposed 35 between the dial and the door of the box and through which the dial is shifted to each succeeding indicating position when the door is opened and said dial is locked from movement when the door is closed, all of which will be hereinafter more definitely described 40 in connection with the accompanying drawings, of which—

Figure 1, is a side elevation of a mail box having my improvements applied thereto, parts of the box being broken away. Fig. 2, 45 is a sectional view through the front portion of the box at a right angle to Fig. 1 and on the line $\alpha\alpha$ of said view. Fig. 3 is a view of the key.

In a detail description of the invention, 50 similar reference characters indicate corresponding parts.

The outer casing 1 of the box is of the usual construction; the upper portion of the box into which the letters are dropped is broken 55 away as illustrated in the drawings, such portion being provided with the usual

hinged door, and owing to the common features thereof, it has not been deemed necessary to illustrate the same. The box is provided with the usual door 2 which is hinged 60 to the bottom of the box at 3; it is through this door that the mail collectors have access to the box in making their collections; this door is provided with the usual hasp and padlock (not shown) and is also a 65 well-known feature of mail boxes as commonly constructed. The side of the box is provided with a sight opening 5 immediately behind which is arranged a dial 6 and the other mechanism co-operating therewith, and all of which is inclosed by an inner casing 4 which forms a separate interior housing for said mechanism. The dial is mounted upon and is rotatable with a hollow spindle 7 which is journaled in the inner and 70 outer casings. Arranged on the face of said dial is a series of spaces upon which the days of the week and the various times within twenty-four hours are inscribed in such position that each inscription, in the 75 rotation of the dial, is caused to appear at the sight opening 5. The dial it will be observed, is arranged to indicate eight collections for each day, and three collections for Sunday, and each collection has a separate 80 tooth on the dial, or for one week's collections the dial makes one complete rotation. The periphery of the dial is provided with a continuous series of ratchets 9 of uniform length and of a length corresponding 85 to the width of the spaces bearing the day and time inscriptions.

10 designates a longitudinally-slidable bar mounted to slide in guides 11 attached to the side of the outer casing. The inner end of 90 this bar is connected to a spring 12 which is secured at one end to the inner casing and exerts a normal pressure upon said bar, while the other end of said bar is pivoted at 13 to the upper arm 14 of a bell crank lever which 100 is fulcrumed at 15 to the casing. At a suitable point on said bar 10 is pivoted a ratchet pawl 16 which engages the teeth 9 on the indicating dial. This pawl is permitted to swing in one direction but is held normally 105 in an operative position by a shoulder 17 which engages the lower side of the bar 10. The lower arm 18 of the bell crank lever is pivoted at 19 to a second slidable rod 20 which moves in guides 21 attached to the inner side of the box. To the lower end of 110 the slidable bar 20 is pivoted a link 22, the

lower end of said link 22 being pivoted at 23 to a side of the swinging door 2. Owing to this arrangement of connecting rod and levers, it will be readily seen that in lowering the door 2 outwardly, the slidable bar 20 will be elevated and through the bell-crank lever the pawl-carrying bar 10 will be moved rearwardly and therewith the pawl 16 to the dotted position; this is the position of the pawl prior to a movement of the dial to its position to indicate the time of the next collection and in elevating or closing the door 2, the pawl-carrying bar 10 is moved forward, the pawl 16 moving from the dotted position to the full position and moving the dial therewith. The dial is locked in each set position by the closed door through means of a slidable bolt 24 movable in a guide 25 secured to the inner side of the box and having a locking head 26 arranged in line with the ratchets 9 and adapted to engage said ratchets when the door 2 is closed. Pivoted to the outer end of the bolt 24 at 27 is a link 28 which is pivoted at 29 to a side of the door 2. When the door is lowered the locking bolt 24 is moved forward to free the ratchets 9 and to permit the pawl-carrying bar 10 to rotate the dial 6 to the position to indicate the time of the next collection, and when said door is closed, the locking bolt 24 engages the ratchets and holds the dial in each set position.

30 is a detent arranged in the rear of the ratchets 9 to prevent any backward movement of the dial. The dial 6 may be rotated independently of the foregoing mechanism which has been described in detail by means of a key 31 which is insertible in the spindle 7; the key, however, can only turn the dial 40 when the bolt 26 is withdrawn by opening the door; this means of setting the dial is utilized in installing the mail box, or at any time when the collections of mail have been neglected by the collector, and consequently, 45 the indication at the dial would not be correct. For example, as the dial is now set, the next collection should be made at 9-30 p. m. on Monday. If the collector should not make such collection for any reason, the next 50 time he opens the box would shift the dial to the next indication and would indicate the time in which he made such collection and would leave such indication exposed as indicating the next collection which would be 55 incorrect. In order to set the dial properly to indicate the periods of collection, the key 31 may be employed.

I claim:

1. The combination with a letter box hav-

ing a sight opening in a side thereof and a door the side portions of which are movable within the box, of a dial having the times for the collections of mail inscribed thereon in positions to be indicated through the sight opening in the box, and ratchets around the periphery of said dial, a slidable bar mounted above the dial, a ratchet pawl carried on said bar and engaging the ratchets on the dial, a bell-crank lever to which said pawl-carrying bar is connected, a slidable bar movable at right angles to the pawl-carrying bar and connected to said bell-crank lever, and a link lever pivoted to the slidable bar moving at right angles to the pawl-carrying bar, said link lever having a pivotal connection to the door of the box and whereby the pawl-carrying lever is actuated and is set to its initial position through the opening and closing of said door.

2. The combination with a letter box having a sight opening in a side thereof and a door the side portions of which are movable within the box, of a dial having the times for the collections of mail inscribed thereon in position to be exposed through the sight opening in the box, and ratchets around the periphery of said dial, of a pawl-carrying bar adapted to actuate said dial, a vertically-slidable bar, a bell-crank lever interposed between the pawl-carrying bar and said vertical bar, a link lever connected to said vertical bar and to the door of the mail box and whereby the pawl-carrying bar is actuated to impart to the indicating dial an advancing movement each time the door is opened, a locking bolt, and a link lever connecting said locking bolt with the door and whereby the dial is locked in each set position when the door is closed after each collection of mail.

3. The combination with a letter box having a sight opening in a side thereof and a door, of a collection-indicating dial provided with ratchet teeth upon its periphery and a collection indication associated with each of said ratchet teeth, a single pawl engaging one of said ratchet teeth at a time, a slidable rod supporting said pawl, an angular lever to actuate said bar, a slidable bar to actuate said lever, a link connected to said last-named bar and to the door and through which the angular lever is actuated.

In testimony whereof I affix my signature, in presence of two witnesses.

CHARLES E. MENDENHALL.
